(57) **CLAIM**

The ornamental design for a humidity sensor, as shown and described.

DESCRIPTION

2. Humidity sensor

2.1 : Perspective

2.2 : Top

2.3 : Cross-section view taken along line 2.3-2.3 in Fig. 2.2

2.4 : Cross-section view taken along line 2.4-2.4 in Fig. 2.2.

In the drawings, the broken lines represent portions of the humidity sensor that form no part of the claimed design; all sides not disclosed in the drawings form no part of the claimed design.
